UNITED STATES PATENT OFFICE.

PETER M. WILSON, OF NIAGARA FALLS, NEW YORK.

EYEWASH BOTTLE.

Application filed August 18, 1925. Serial No. 50,909.

My invention relates to an improved eye-wash bottle.

In treating the eye with liquids in the case of injuries or irritation it is customary 5 to employ an eye-cup, a small receptacle usually of glass adapted to fit closely about the eye. The protection of the eye is an important part of industrial safety work, and in many cases immediate treatment is

10 necessary if any treatment is to be effective.

One of the most commonly employed eye-washes is a dilute solution of boric acid. Such boric acid solutions are usually made by dissolving boric acid in water at an 15 elevated temperature and separating precipitated boric acid after cooling the solution to ordinary temperature.

Usually, such solutions are kept in stoppered bottles from which portions are withdrawn 20 for use in an eye-cup as necessary, but unless both the bottle of solution and the eye-cup are together, the treatment cannot be quickly or conveniently carried out. With a separate eye-cup and solution bottle, 25 the two can be easily separated so that they are not immediately available in the case of accident, and this is particularly true in establishments where intensive industrial operations are being carried out.

30 My invention provides an improved combined eye-cup and eye-wash bottle of construction such that the eye-cup and the solution cannot be separated while at the same time the solution is kept in a closed container until ready for use. My invention also provides for protection of the eye-cup until it is to be used, and has several other important advantages as will appear from the following detailed description.

40 The accompanying drawings illustrate an embodiment of my invention from which the characteristic features and advantages of my invention will be apparent. In the drawings, Fig. 1 is a vertical sectional view 45 of an eye-wash bottle embodying the invention, and Fig. 2 is a section on line 2-2 of Fig. 1.

50 Referring to the drawings, my improved combined eye-cup and eye-wash bottle is made up of a bottle portion 3 adapted to contain a portion of the eye-wash and an eye-cup portion 4 formed integrally with the bottle portion and joined thereto through the neck portion 5. The eye-cup portion is provided with a rim of contour 55 adapted to fit about an eye. Between the

interior of the eye-cup portion and the interior of the bottle portion, there is a communicating passage 6. A stopper 7 is arranged to close this passage and to retain 60 liquid in the bottle portion. This stopper may with advantage be provided with a depending rim 8 arranged to cover the rim of the eye-cup and to protect the eye-cup portion from contaminating influences when 65 the stopper is in place in the bottle. The combined eye-cup and bottle and the stopper may be made of glass.

For use in industrial establishments, a 70 number of bottles of the construction illustrated in the drawings are provided at convenient locations and are kept filled with appropriate solutions for treating the eye in connection with the work involved. The solution is retained in the bottle portion 75 where it is protected by the close fitting stopper until it is to be used. Where the stopper is provided with a depending rim as illustrated, the eye-cup portion also is protected until it is to be used. In case of 80 accident, the stopper is removed and after placing the eye-cup against the eye the bottle is inverted by tilting back the head so that the eye-wash solution runs from the bottle portion into the eye-cup portion and 85 is there brought into contact with the eye. After use, the eye-wash bottle may be sterilized, refilled and restoppered for use when next it becomes necessary.

90 It will be apparent that, with an eye-wash bottle of the construction provided by my invention, the eye-wash solution and the eye-cup are necessarily together when necessity for their use arises and that the only 95 operation involved in making the eye-wash solution available for treating the eye is the removal of the stopper. By making the bottle of rigid construction, accidental displacement of the solution is made impossible. To avoid accidental infection, the bottle portion is made of a size just sufficient to hold a portion of the eye-wash solution for a single treatment so that the bottle must be refilled every time it is used.

100 My invention thus provides an improved eye-wash bottle of construction such that the supply of eye-wash solution and the means for treating the eye with the solution are necessarily kept together, in which 105 the chance of infection such as is encountered in the use of a common eye-cup may be eliminated, and in which the eye-cup as

well as the eye-wash solution may be protected from contaminating influences.

I claim:

An eye-wash bottle comprising a bottle portion adapted to contain a portion of the eye-wash, said bottle portion having formed integrally therewith an eye-cup portion having a rim of contour adapted to fit about

an eye, the interior of the eye-cup portion having a passage communicating with the interior of the bottle portion, and a stopper adapted to tightly fit said passage, said stopper having a protective bell-shaped cover for the eye cup attached thereto.

In testimony whereof I affix my signature.

PETER M. WILSON.
